Brookdale
Attorney.

UNITED STATES PATENT OFFICE.

WILLIAM W. SHOE, OF PHILADELPHIA, PENNSYLVANIA.

PAVEMENT-BREAKING DEVICE.

Application filed April 4, 1924. Serial No. 704,148.

To all whom it may concern:

Be it known that I, WILLIAM W. SHOE, a citizen of the United States, residing at Philadelphia, in the county of Philadelphia, 5 State of Pennsylvania, have invented a new and useful Pavement-Breaking Device, of which the following is a specification.

My invention relates to pavement breaking devices. The object is to provide improved means for making the initial break in a pavement, especially of blocks, bricks or the like, when it becomes necessary to take up a section of same.

Referring to the drawings, which illustrate, merely by way of example, suitable means for effecting my invention;

Fig. 1 is a side elevation of two blocks with the key for dislodging the same.

Fig. 2 is a plan view of same.

Fig. 3 is a perspective view of the key.

Fig. 4 is a side elevation of a modification.

Fig. 5 is a perspective view of the modified key member.

Fig. 6 is a cross-section showing a modification of the engaging recess.

Similar numerals refer to similar parts throughout the several views.

It is well known that when a pavement is once laid of bricks, or blocks, or similar close lying units, especially for street surfaces, it is difficult to make the initial break in same, when it becomes necessary to take up a section of the pavement, for repairs, for laying 30 pipes or the like.

My invention overcomes the difficulty by providing means for applying the necessary force beneath the abutting edges of a pair of paving elements, in order to lift the same 40 out of their normal position, and thus provide a space in which to insert a suitable tool, such as a crowbar, for dislodging the pavement surrounding said initial opening.

In Fig. 1 is shown paving blocks 7 and 8, 45 with the key or body 9 positioned between the abutting ends of said blocks. In the form shown in Figs. 1, 2 and 3, this key or body 9 is formed with curved sides, tapering from the bottom toward the top, and 50 the two abutting blocks have their ends preferably cut or formed with curved surfaces corresponding to the formation of body 9, as shown in Fig. 1. From such cooperating formations, it results that a portion of the

engaging surface of body 9 is vertically beneath the engaged surface of the block, so that the upward movement of body 9 causes corresponding movement of the adjacent blocks and consequently their dislodgement. The curved formation is substantially in the 55 arc of a circle, the center of which is at upper remote edge of the block, as at 10. This obviously facilitates the movement of the two abutting ends, in the direction of the arrow, about the said centers 10, when 60 the member 9 is lifted. The member 9 is provided with suitable means for securing a lifting device thereto. In the example shown in Figs. 1, 2 and 3 this consists of a threaded opening as at 11, into which an eye-bolt may 65 be secured, which eye-bolt is then connected to a suitable lifting jack or other device. When the pavement is laid the opening 11 is preferably filled with wax or other suitable substance which is easily displaced, but 70 which normally serves to keep out dirt or other foreign substances.

In Figs. 4 and 5 is shown a key or dislodging body 12 which is provided with the flanges 13, adapted to lie beneath the abutting ends of the blocks. While this device 75 will undoubtedly cause an initial break in the pavement, it may require more lifting force, since it makes no provision for the curved movement of the lower edges of the 80 abutting ends, and thus requires a certain amount of give or compression between these blocks and those adjacent thereto, or else a breaking of the blocks operated upon, which 85 is usually not a serious matter.

Instead of the threaded opening 11 as in Fig. 1, I show a U-shaped opening 14 in Fig. 6, which is adapted to receive a hook in connection with a lifting device. This 90 will in some cases be more desirable. These 95 of course are only given as examples of suitable methods of securing the lifting mechanism to the key or dislodging device.

What I claim is:—

1. A pavement breaking device, comprising a body permanently positioned between abutting pavement elements, said body having engaging surfaces extending beneath adjacent portions of said pavement elements so that upward vertical movement of said body 100 will dislodge said elements.

2. A pavement breaking device, comprising a body permanently positioned between

abutting pavement elements, said body having curved engaging surfaces extending beneath adjacent portions of said pavement elements so that upward vertical movement of said body will dislodge said elements.

3. A pavement breaking device, comprising a body permanently positioned between abutting pavement elements, said body hav-

ing engaging surfaces extending beneath adjacent portions of said pavement elements so that upward vertical movement of said body will dislodge said elements, and means for removably securing the said body to a lifting device.

WILLIAM W. SHOE
